TIME LOCK

Clarence G. Smeaton, Milwaukee, Wis.

Application January 4, 1934, Serial No. 705,178

8 Claims. (Cl. 70—26)

My invention relates to improvements in time locks.

The object of my invention is to provide a lock for a door, drawer, or other openable member which is provided with a timed mechanism to control a locking device separate from the locking device controlled by a key.

Another object of my invention is to provide a dual system of locking devices for a drawer or door or similar closure member, one of the locking devices in my dual system being a standard type of locking member, and the other device being used as a separate time controlled locking device set in locking position and opened in a definite sequence in the cycle of operation of said parts.

Another object of my invention is to provide a time lock in the form of an auxiliary locking device which is automatically operable in conjunction with a main locking mechanism automatically and without specific attention by the operator or person locking or unlocking a drawer or door with which the mechanism is installed.

Another object of my invention is to provide a time lock device, the operation of which is constituted by the normal operation of a main or principal locking device, but which is so mechanically divorced in its time lock operation from the mechanical devices comprising the principal lock that physical damage to the principal locking mechanism will not interfere with the time lock mechanism.

In the drawings:

Figure 1 is a vertical section through the front portion of a drawer equipped with my improved time lock.

Figure 2 is a section on line 2—2 of Fig. 1.

Figure 3 is a section on line 3—3 of Fig. 1.

Figure 4 is a section on line 4—4 of Fig. 3.

Figure 5 is a section comparable to that shown in Fig. 1, and disclosing the principal locking device in almost complete retraction of the locking bolt, and my time locking device in almost complete bolt locking position.

Figure 6 is a view similar to the one shown in Fig. 1, with the principal locking device in unlocked position and the time lock device almost in position for bolt retraction to unlocked position.

Like parts are identified by the same reference characters throughout the several views.

I am aware that many devices have comparatively recently been developed for the provision of a locking device wherein preliminary movement of the principal locking mechanism insti-

tutes the operation of a time device which, in a certain sequence of movements, permits the retraction of the principal locking bolt. However, in such devices the association of the hand operated portions of the principal locking device with the time mechanism for retracting the principal locking bolt causes mechanical difficulties which may easily interfere with the normal authorized unlocking operation.

Likewise, many of the time locking devices heretofore devised have required a manual setting of the time lock mechanism upon each occasion when the drawer, safe door, or other closure member is to be locked, and failure to manually set the device for operation leaves the closure member merely subject to the protection offered by ordinary key or combination locks such as are prevalent upon the market.

My lock mechanism is installable in a small compartment 10 which may take the form of an enclosure metallically boxed by the sheet metal 11. This boxed enclosure may be disposed as a part of the front wall of a drawer slidable into a drawer frame 12, or the box 11 may form a structural element in the door of a safe (not shown). In the description hereinafter set forth it is assumed that the box 11 forms a part of the front wall of a drawer and that this drawer is provided with handles 13 and 14, handle 13 being an operating handle for the lock mechanism, and handle 14 comprising a "dummy" handle merely to comprise a door "pull".

In my new time lock mechanism shown in the drawings, I provide certain mechanisms which may be divided into classifications which I shall hereinafter describe as "principal locking mechanism" and "time lock mechanism", respectively.

Principal locking mechanism

In each of the views shown in Figs. 1, 5, and 6, the principal locking mechanism is disposed as to its major physical structure at the left of the center of each of said views and includes the following structural elements.

A principal locking bolt 15 is mounted for reciprocation through an aperture in the box 11 at 16 and through a slide bracket 17. This principal locking bolt 15 is receivable in a recess 18 in the frame 12 to prevent the drawer from being slidably removed from the frame, and the operation of moving the principal locking bolt to and from locking position is a manual one accomplished by rotation of the handle 13 shown in dotted lines in Fig. 1, and in full lines in Fig. 3. This handle 13 is mounted upon a handle shaft 55

20 to the inner end of which is secured for rotation therewith, a manual lock plate 21 provided with spaced lugs 22 shown in Fig. 4.

- 5 A principal lock arm 23 extending from lock arm pin 24 on the plate 21 to a principal bolt pin 25 on the principal bolt 15 is fulcrumed upon a post pin 26 so that when the plate 21 is rotated the principal bolt 15 is moved to or from locked position.
- 10 A key lock bracket 27 extending into the compartment 10 from the front wall 28 of the drawer 11 provides a mounting for a stop 29 slidable to and from engagement with the lugs 22 on the plate 21. This stop is controlled by levers and linkage connected to the lock plug 30' of a key lock 30, shown clearly in Fig. 1, where it will be seen that a crank 31 on the key lock plug 30' is connected with a connecting link 32, extending to a lever 33 mounted for pivotal movement upon 20 a fulcrum post pin 34. The other end of the lever 33 is provided with a slot at 35 to receive a pin 36 extending from the stop 29.

From the above description it will be seen that when the key lock is rotated so as to withdraw the stop 29 from between the lugs 22 manual rotation of the shaft 20 and the plate 21 will cause the principal locking bolt 15 to be adjusted as desired and I have therefore described the principal locking mechanism which, as stated above, appears at the left of Figs. 1, 5, and 6 in my drawings.

Time lock mechanism

- 35 A slotted ear 40 forming a part of the plate 21 embraces a pin 41 upon a time lock control bar 42, which is mounted in brackets 43 and 44 for reciprocation laterally of the drawer and the opposite end of the time lock bar 42 is provided with a spring dog or pawl 45, provided with a spring 46 which normally maintains the pawl against a stop 47. This stop limits the oscillation of the pawl 45 about its pivot pin 48.

The pawl 45 is normally disposed so that its point 49 in its path of movement in accord with the reciprocation of the time lock control bar 42 will impinge upon time lock plate 50 and engage a notch at 51 therein.

In the alternative construction shown in Fig. 5, a cam dog 100 is substituted for the notch 51 in plate 50 for reasons which will now be explained.

In some installations, and in conjunction with some types of spring clock-work, it is undesirable to have the clock winding operation terminate in a snap action which may result when the point 49 of the pawl 45 escapes from the notch 51. In such case, I provide the cam dog 100 pivoted upon a pin 101 and urged by spring 102 so that the dog stop arm 103 impinges upon the clock spring shaft 52. The cam surface 104 is then offered for interaction with the point 49 of the pawl 45, and as the pawl 45 passes over the cam surface 104 of the dog, the last forward urging of the winding operation is tapered off in such a way that the clock mechanism suffers no shock when the point 49 ceases to contact the cam surface 104 at the extreme left movement of the time lock control bar 42.

70 Upon the return reciprocation to the right of the bar 42, the cam dog 100 may swing upon the pivot pin 101, or the pawl 45 may swing upon its pin 48 so that the two parts may "clear" each other.

75 Since the time lock plate 50 is mounted upon a

clock spring shaft 52, movement of the time lock bar 42 and the point 49 of the pawl 45 to the left as indicated in Figs. 1, 5, and 6, will cause the clock spring upon shaft 52 to be "wound up". At the same time that this winding operation is 5 taking place, a pin 53 upon the time lock plate 50, is caused to rotate with the plate, and by reason of its engagement in the slot of a time bolt bar 54, causes the bar to rotate upon its pivot post pin 55. The other end of the time bolt bar 10 54 is then raised against a pin 56 on the time lock bolt 57, thus causing the time lock bolt 57 to move to the position indicated in Fig. 6. During the movement of the time lock bolt from the position shown in Fig. 1 to the position shown in 15 Fig. 6, a time lock stop block 60, mounted for reciprocatory movement with rods 61 is caused to receive the pressure of compression springs 62 by reason of the movement of a slide block 63 under the influence of a bolt stop lever 64 mounted 20 for pivotal movement upon post pin 65. The bolt stop lever is provided with slots as indicated clearly in Figs. 1, 5, and 6, and pins 66 and 67 upon the slide block 63 and the time lock plate 50, respectively, engage with the lever to place the 25 springs 62 under compression between the stop block 60 and the slide block 63 as the winding operation is being completed.

At no time in the sequence of operations is the drawer unlocked. Manual lock bolt 15 is only 30 partly retracted when time lock bolt 57 is engaged in its recess.

As soon as the time lock bolt 57 is set in complete locking position, the stop block 60, having theretofore been placed under compression by the 35 springs 62, snaps into the position indicated in Fig. 6 to prevent the time lock bolt from being displaced from locking position.

As the clock mechanism indicated generally in the box 70 unwinds after the initial time bolt 40 setting operation is complete, the time bolt bar 54 is returned to the position indicated in Fig. 1, and goes through an intermediate stage shown in Fig. 6, so that but for the stop block 60, the time bolt 57 would be slowly returned to unlock- 45 ing position. However, in keeping with my desire to maintain the drawer 11 in fully locked condition until the expiration of the entire period for which the clock-work mechanism 70 has been set, I provide in the bolt stop lever 64 and the 50 springs 62 means for maintaining the stop block 60 in the position shown in Fig. 6 until the lower end of the stop lever 64 is in the extreme right hand position, by which time the slide block 63 has moved upon the rods 61 so as to impinge 55 against the stop pin 47 and ride over the edge surface of time lock plate 50 until the pawl is positioned as indicated in Fig. 1 in readiness for another time lock setting operation. This is of 60 importance since any unauthorized manipulation of the handle 13 will cause the pawl 45 to again contact the time lock plate 50 and engage the notch 51 therein either to prevent the further 65

70 It will be noted in Figs. 5 and 6 that when the time lock control bar 42 slides to the extreme 75 right hand position, the pawl leaves its position against the stop pin 47 and rides over the edge surface of time lock plate 50 until the pawl is positioned as indicated in Fig. 1 in readiness for another time lock setting operation. This is of 70 importance since any unauthorized manipulation of the handle 13 will cause the pawl 45 to again contact the time lock plate 50 and engage the notch 51 therein either to prevent the further 75

time clock rotation of the plate 50, or to actually wind up the clock mechanism again for another 15 or 20 minute sequence of operations.

It will be likewise noted from the above description, that the time lock mechanism is so completely divorced from the mechanical parts incident to the manual locking of the drawer that any rough usage or forceful manipulation of the handle 13 can do nothing more than reset the time mechanism. The time mechanism cannot be forced.

I claim:

1. In a lock for a closure member provided with a manually controllable lock bolt, a time mechanism and a separate time controlled lock bolt interconnected with the manually controllable lock bolt only through a time lock setting mechanism.

2. In a lock for a closure member provided with a manually controllable locking mechanism, a separate locking mechanism for said closure member, means interconnecting the manual lock and the separate lock, whereby to move the separate lock to locked position in the movement of the manual lock to unlocked position, and a clock mechanism for releasing the separate lock.

3. In a lock for a closure member provided with a manually controlled lock bolt mechanism and a separate time controlled lock bolt mechanism, a time lock bolt control bar interconnecting the two lock bolt mechanisms, whereby in the movement of the manually controlled lock bolt mechanism to unlocked position the time lock bolt control bar is moved to time lock bolt setting position, and a clock mechanism for returning the time lock bolt to unlocked position.

4. In a lock for a closure member provided with a key lock, a manual locking bolt controlled by the key lock, and a time locking bolt, a manual lock plate connected with the manual locking bolt to move it to and from locked position, a time lock control bar connected to the manual locking plate, a clock mechanism for the time locking bolt, and a time lock plate for rotation by said clock, means interconnecting the time lock plate and the time locking bolt, and a pawl upon the time lock control bar for moving the time lock plate to time lock setting position.

5. In a lock for a closure member provided with a key lock, a manual locking bolt and a time locking bolt, a manual lock plate connected with

the manual locking bolt to move it to and from locked position, a time lock control bar connected to the manual locking plate, a clock mechanism for the time locking bolt, a time lock plate for rotation by said clock, means interconnecting the time lock plate and the time locking bolt, a pawl upon the time lock control bar for moving the time lock plate to time lock set position, a stop to prevent movement of the time lock bolt to unlocked position, and connections between said stop and the time lock plate, whereby to remove the stop and permit the time lock bolt to move to unlocked position.

6. In a lock mechanism a lock bolt and a time clock mechanism connected with the bolt to move to lock set position, a stop block, connections between the clock mechanism and the stop block for resiliently urging the stop block into position to prevent retraction of the bolt, said connections being provided with a retracting block for positively urging the stop block to a position whereby to permit the bolt to move to unlocked position.

7. In a lock mechanism a lock bolt and a time clock mechanism connected with the bolt to move to lock set position, a slide bar and a stop block 25 slidable thereon to and from a bolt retraction stopping position, a retracting block secured to the slide rod, a slide block between the stop block and the retracting block, resilient means between the slide block and the stop block, and connections 30 between the clock mechanism and the slide block, whereby to urge the slide block against the resilient means in the movement of the bolt to lock setting position, and to urge the slide block 35 against the retracting block in the movement of the clock mechanism to bolt withdrawn position.

8. In a lock, a manual lock bolt and manually operable connections for moving said lock bolt to and from locked position, a separate time lock bolt interconnected with the manual lock bolt for 40 positive movement against gravity to locked position, a time lock mechanism including a clock and means for setting the clock, said means being operatively connected to the manually operable connections for the lock bolt, a movable stop to 45 block the retraction by gravity of the time lock bolt to unlocked position, and means to interconnect said stop with the time clock, whereby to move the stop and permit the gravity retraction of the time lock bolt.

CLARENCE G. SMEATON.
